UNITED STATES PATENT OFFICE

1,940,347

REFRIGERATION SYSTEM WITH MULTIPLE
IMPELLERS AND SHELL EVAPORATORS

Norman H. Gay, Los Angeles, Calif.

Application January 15, 1932. Serial No. 586,928

9 Claims. (Cl. 62—160)

This invention relates to improvements in heat transfer means for refrigerating systems, and is illustrated as applied to the brine tank and ice field portion of an ice manufacturing plant.

5 One of the features of the present invention is the provision of an impeller system for causing brine or other refrigerant mediums to circulate in maximum volume through an evaporator and in still greater volume through that portion of 10 the system where it is desired to cause freezing or congealing of the product.

Another feature of the present invention is the provision of a refrigerating structure with associated parts whereby a high velocity of brine or 15 other liquid flow through the ice field or like structure may be accomplished with a given size of evaporator.

Another feature of the present invention is the provision of a tubular evaporator having a special 20 arrangement of tubes not heretofore used in refrigerating structures, which said arrangement of tubes permits a large amount of space for separation of liquid and gaseous refrigerant before said gaseous refrigerant leaves said evaporator.

25 Another feature of the invention is the provision of means for moving the brine at a high rate of speed in cycle.

Further features of the invention concerning details of construction of the several parts, will 30 appear in the course of the following specification and claims.

An illustrative form of practicing the invention is shown on the accompanying drawings, in which

Figure 1 is a horizontal diagrammatical plan, 35 with parts in section, showing the relationship of the evaporator, brine impelling system and ice field to one another.

Figure 2 is a vertical sectional view substantially on line 2—2 of Figure 1.

40 Figure 3 is a vertical detail view on a larger scale, partly in section, of the hood end of the evaporator.

Figure 4 is a vertical sectional view through the evaporator shell on a larger scale.

45 Figure 5 is a detail sectional view on line 5 of Figure 4.

Figure 6 is a sectional view, on a larger scale, of the brine impelling structure.

Figure 7 is a sectional view on line 7—7 of 50 Figure 6, of the shaft stabilizing members.

Figure 8 is a sectional view, on line 8—8 of Figure 6.

In the drawings, the evaporator structure is shown employed with an ice field which is surrounded by tank walls 10 of heat insulating ma-

terial. An offset 11 of these walls provides a space for the motor for driving the brine impeller. Within the tank are the longitudinal partitions 12 which extend from top to bottom of the tank to cause a circulation of the brine as will be described hereinafter, and for this purpose terminate short of the end walls 10. Within the tank are shown cans 13 of usual type, which may be arranged and supported in any usual way. Opposite the offset portion 11, a clear space is provided within which the evaporator may be located. Within this space the angularly directed walls 12 extend from partitions 12a toward the offset walls 11 (Figure 1) and then are closed by an end wall 12b, so that the walls 12, 12a, and 12b extend continuously, and permit passage of brine from one side thereof to the other only at their ends and through a hood in wall 12b as will be described hereinafter.

It will be understood that the illustrative form sets out what may be termed a "twin" type of ice field and evaporator circulating system, since the two ice fields are fed by branched circulating currents of brine; and that the operation is the same if one ice field is shut off or if it be eliminated entirely.

The evaporator comprises the shell 15 having a conical extension 16 terminating in a shell hood 17. The conical extension 16 has a split marginal flange 18 which may be clamped upon the end of the shell 15 by the bolt 19 (Figs. 2 and 3).

The evaporator, besides the jacket shell 15, includes a pair of end or header plates 20, 21, which are preferably secured in the shell by a welded seam 22, (Figure 5). These header plates are 90 provided with aligned holes through which pass the brine tubes 24, which preferably are secured in the headers by rolling, or in another manner which provides a security against longitudinal movement and a proper packing of the joints.

Leading to the bottom of the chamber formed by the shell and its headers is an inlet pipe 30 for liquid refrigerant, while a larger off-comer pipe 31 provides for the withdrawal of vaporized refrigerant from the shell chamber. It will be noted that the tubes 24 do not fill the shell, but leave free a space equal to about one-quarter of the cross sectional area of the shell. It will be understood that in operation the shell is filled with liquid refrigerant to a level as indicated in

Figure 4, so that a considerable free space is left in which gaseous refrigerant may separate from liquid refrigerant, prior to withdrawal from the shell.

The impeller system comprises a shaft 40 lo-

cated in bell 41 having a flange 42 secured to the offset wall 11 (Figure 6), so that the bell itself extends through this wall and is sealed with respect thereto. At each end of the bell is provided a bearing 43, 44 for the shaft. At the inner end of the bell are arranged the strut or stiffener rods 45 which extend radially away from the shaft and are secured to brace members 46 joined to the hood 48 which is secured to the wall

- 10 12b. Within the hood 48, the shaft 40 carries an impeller fan or propeller blade 50 having its hub 51 keyed and secured to the shaft. Beyond the impeller blading 50, the shaft is provided with a spacer sleeve 52 at the end of which is provided 15 a second impeller blading 53 which likewise has its hub 54 keyed to the shaft 40. A locking cap 55 of streamline form is preferably screwed to the end of the shaft and held against rotational movement relative to the shaft by a screw 56 20 passed into the hub 54.

At the end of the shaft 40, projecting from the outer end of the bell 41 is keyed and secured a pulley 57 which is driven by any suitable motive power.

- 25 Within the bell is provided a partition wall 58 which carries the packing 59 around the shaft 40, which may be clamped into sealing condition by a gland 60.

In operation, liquid refrigerant is delivered 30 through the pipe 30 and gaseous refrigerant is drawn off through the off-corner pipe 31 to a compressor for recompression, condensation and return in cycle. Any desired type of compressor-condenser system may be employed, and owing 35 to the well-known structures of such plants, they have not been illustrated.

The pulley 57 is then set in rotation with its shaft 40 so that the impeller bladings 50, 53 are driven and cause a movement of the brine or 40 other liquid (hereinafter referred to as "brine") from the space at one side of the partition 12 (above, Figure 1) to the other side of the partition (below, Figure 1). The impeller 50 will, due to the greater resistance of the tubes to passage of brine (or if desirable, may be designed to), 45 deliver a greater volume of brine through the partition 12b than is forwarded by the blading 53 through the shell 15. Hence there is a constant escape of brine from between the heads 48 and 50 17 into the space surrounding the shell 15 (Figure 1), and thus a higher head of pressure may be built up at the two sides of the walls 12a, 12b, than if all the brine were forced through the tubes. For example, heads of 6 to 8 inches and 55 more may thus be developed. The impeller 53, however, continuously operates to force the largest consistent quantity of the brine through the evaporator tubes.

Owing to the friction created within the tubes 60 of the evaporator shell, only a definite quantity of brine may be driven therethrough at a given pressure. The impeller blading 53 causes an increase in this pressure receiving the brine at the pressure head given it by the blading 50 and 65 by this increase in pressure accelerating the movement of the brine through the tubes. While within the tubes, a very rapid and energetic cooling of the brine occurs so that it is ultimately delivered at the other end of the shell (bottom of Figure 1) in a colder condition. It then minglesthe with the brine which has escaped between the hoods 48 and 17 and because of the increase in volume due to the addition of this escaped brine, and the head created and maintained by 70 impeller 50, circulates rapidly past the cans to

the end of partition 12, in either direction, and then returns back to the hood 48 for repumping by the blading 50. The very rapid circulation thus effected causes a quick chilling of the materials in the cans. It will be noted that even 80 the exterior of the shell is thus employed for cooling brine, and that this cooling effect is produced on brine which has the same temperature as the brine entering the tubes.

It will be understood that this propeller type 85 of blading has a characteristic like that of the centrifugal pump in that as the resistance to flow builds up the circulated volume drops. Hence, for any given speed of the impeller 53, 90 no matter how much care is taken for enclosing the flow between the impeller 53 and the shell, the volume will not be increased owing to the relatively fixed friction losses at given volumes, of brine traveling within the brine tubes.

It may be pointed out that with the impellers 95 20 inches in diameter, about 1100 cubic feet of brine may be handled per minute, and with 30 inch impellers, about 1600 feet per minute at normal operating speeds. Of this volume, about 400 cubic feet may be passed through a 150 tube 100 evaporator of standard construction and 750 feet through a 250 tube evaporator. By providing the two impellers and an escape opening between the impellers, the first impeller operates to deliver its full quantity of brine at its normal pressure 105 head whereby to cause the regular flow of brine in the can portion of the circuit. The second impeller 53 operates to increase the relative pressure head on the brine passing through the tubes over and above the head or level within the 110 space surrounding the evaporator and thus cause the greatest flow of brine possible through the tubes.

By providing the offset 11 in the walls of the ice tank it is possible to house the ice tank in 115 a rectangular building, without interference with the space afforded the ice cans in the ice field proper, and at the same time to have the impeller motor located within the building. Further, this arrangement in conjunction with the 120 walls 12a, 12b permits the use of a relatively short drive shaft and a close connection between the motor and the shaft, whereby space is saved. The motor M is supported on a shelf 100 carried by a bracket secured to the vertical offset 125 wall 11 of the brine tank, and preferably a strut connection 101 is provided between the outer edge of this shelf and the housing 41 (Figure 2).

It will be understood that a particular feature 130 of the invention is the provision of the multiple impellers, one serving to effect a general circulation of brine, and the other to move a part of the brine through the evaporator structure; together with means for operating the impellers; and that the invention is not limited in these 135 respects to the illustrated form in which a common driving means and coaxial impellers are provided.

Further, it will be understood that the structure is applicable for the cooling and circulation 140 of any heat exchange medium, which must be understood as included broadly under the term "brine" as used herein; and that the heat exchange medium may be employed for various purposes at the points described herein as an 145 "ice field". The illustrative employment of brine and an ice field as means of practicing the invention is intended as a specific example only, since the invention may obviously be employed and this example changed in many ways with- 150

out departing from the scope of the appended claims.

Having thus described the invention, what I claim as new and desire to secure by Letters Patent is:

1. In a refrigeration system operating with a circulating heat-exchange medium, a heat-yielding element, a heat-absorbing element, first impeller means for establishing a circulation of the medium over said heat-yielding element, second impeller means for passing a part of the circulating medium over said heat-absorbing element, and a by-pass for the remaining part of the circulating medium around the heat-absorbing element. 80
2. A refrigeration system comprising a brine tank, a partition in said tank to control the direction of flow therein, an evaporator located in said tank at one side of said partition, and two impellers, one of said impellers being arranged to move the brine from one side of said partition to the other whereby to establish a circulation of the brine, and the other impeller being arranged to force a portion of the circulated brine into contact with said evaporator, the remaining portion of the circulated brine being permitted to bypass the evaporator. 85
3. A refrigeration system comprising a brine tank, a partition in said brine tank to control the direction of flow therein and having an offset to provide wider and narrower compartments, an evaporator located in said wider compartment, a first impelling means located in the offset portion of said partition for moving the brine from one side of said partition to the other whereby to establish a brine circulation, a second impelling means to force a portion of said circulating brine over surfaces of the evaporator, the remaining portion of the circulated brine being permitted to bypass said evaporator. 90
4. A refrigerating system comprising a brine tank, a partition in said tank to control the direction of flow therein and having an offset whereby to provide a wider and a narrower compartment adjacent one another and separated by said offset of the partition, a shell-and-tube evaporator located in said wider compartment, a first impelling means for forcing brine from said narrower compartment into said wider compartment whereby to establish a circulation of brine, and a second impelling means for forcing brine through said evaporator. 95
5. A refrigerating system comprising a brine tank having an offset in one wall thereof, a partition in said tank to control the direction of flow therein and having an offset in alignment with said wall whereby to provide a narrower compartment between said offsets and a wider compartment adjacent said narrower compartment, an evaporator located in said wider compartment, a shaft extending through said offsets, two impelling means on said shaft, one of said impelling means serving to move brine from said narrower compartment into said wider compartment, the other said impelling means serving to move brine over said evaporator, and means located within said tank offset for driving said shaft. 100
6. A refrigerating system comprising a brine tank, a partition in said tank to control the direction of flow therethrough and having an offset, a shell-and-tube evaporator provided with a hood member, a hood member in said partition offset, said hoods being axially aligned and spaced apart, individual impellers in said hoods, and means for driving said impellers. 105
7. A refrigerating system comprising a tank for a heat-exchange fluid, a partition in said tank to control the direction of flow therethrough and having an offset provided with a hood member surrounding an aperture, a shell-and-tube evaporator provided with a hood member at one end, individual impellers in said hood members, and means for driving said impellers, said hoods being spaced apart so that the impeller in said partition offset may establish a circulation of fluid in said tank around said partition and back to said partition offset impeller, and the impeller in the evaporator hood member may force a portion only of the circulating fluid through said evaporator, the remaining fluid bypassing the evaporator. 110
8. In a refrigeration system operating with a circulating heat-exchange medium, a heat-yielding element, first impeller means for establishing a circulation of the medium over said heat-yielding element under a substantially constant head of pressure, an evaporator comprising a cylindrical shell mounted with a horizontal axis and having heads, substantially horizontal tubes secured in said heads and located in the lower portion of said shell, means for supplying liquid refrigerant into said shell whereby it may establish a level therein above said tubes, said shell providing an accumulator space above the liquid level for the separation of gaseous from liquid refrigerant, an outlet for gaseous refrigerant from said accumulator space, second impeller means for establishing a flow of a portion of said circulating heat-exchange medium through said tubes, and a by-pass for the remaining part of the circulating medium around said evaporator, whereby an energetic cooling of the portion of said medium passing through the tubes is produced and the gases of vaporization in said evaporator are permitted to separate from refrigerant liquid within said accumulator space. 115
9. In a refrigeration system operating with a circulating heat-exchange medium, a heat-yielding element, first impeller means for establishing a circulation of the medium over said heat-yielding element under a substantially constant head of pressure, an evaporator comprising a cylindrical shell mounted with a horizontal axis and having heads, substantially horizontal tubes secured in said heads and located within the lower three-quarters of the upright cross-sectional area of said shell, means for supplying liquid refrigerant into said shell whereby it may establish a level therein above said tubes, said shell providing an accumulator space above the liquid level of substantially one-quarter of the upright cross-sectional area of said shell for the separation of gaseous from liquid refrigerant, an outlet for gaseous refrigerant from said accumulator space, second impeller means for establishing a flow of a portion of said circulating heat-exchange medium through said tubes, and a by-pass for the remaining part of the circulating medium around said evaporator, whereby an energetic cooling of the portion of said medium passing through the tubes is produced and the gases of vaporization in said evaporator are permitted to separate from refrigerant liquid within said accumulator space. 120
10. In a refrigerating system comprising a brine tank, a partition in said tank to control the direction of flow therein and having an offset, a shell-and-tube evaporator provided with a hood member, a hood member in said partition offset, said hoods being axially aligned and spaced apart, individual impellers in said hoods, and means for driving said impellers, a cylindrical shell mounted with a horizontal axis and having heads, substantially horizontal tubes secured in said heads and located within the lower three-quarters of the upright cross-sectional area of said shell, means for supplying liquid refrigerant into said shell whereby it may establish a level therein above said tubes, said shell providing an accumulator space above the liquid level of substantially one-quarter of the upright cross-sectional area of said shell for the separation of gaseous from liquid refrigerant, an outlet for gaseous refrigerant from said accumulator space, second impeller means for establishing a flow of a portion of said circulating heat-exchange medium through said tubes, and a by-pass for the remaining part of the circulating medium around said evaporator, whereby an energetic cooling of the portion of said medium passing through the tubes is produced and the gases of vaporization in said evaporator are permitted to separate from refrigerant liquid within said accumulator space. 125
11. In a refrigerating system comprising a brine tank, a partition in said tank to control the direction of flow therein and having an offset, a shell-and-tube evaporator provided with a hood member, a hood member in said partition offset, said hoods being axially aligned and spaced apart, individual impellers in said hoods, and means for driving said impellers, a cylindrical shell mounted with a horizontal axis and having heads, substantially horizontal tubes secured in said heads and located within the lower three-quarters of the upright cross-sectional area of said shell, means for supplying liquid refrigerant into said shell whereby it may establish a level therein above said tubes, said shell providing an accumulator space above the liquid level of substantially one-quarter of the upright cross-sectional area of said shell for the separation of gaseous from liquid refrigerant, an outlet for gaseous refrigerant from said accumulator space, second impeller means for establishing a flow of a portion of said circulating heat-exchange medium through said tubes, and a by-pass for the remaining part of the circulating medium around said evaporator, whereby an energetic cooling of the portion of said medium passing through the tubes is produced and the gases of vaporization in said evaporator are permitted to separate from refrigerant liquid within said accumulator space. 130
12. In a refrigerating system comprising a brine tank, a partition in said tank to control the direction of flow therethrough and having an offset, a shell-and-tube evaporator provided with a hood member, a hood member in said partition offset, said hoods being axially aligned and spaced apart, individual impellers in said hoods, and means for driving said impellers, a cylindrical shell mounted with a horizontal axis and having heads, substantially horizontal tubes secured in said heads and located within the lower three-quarters of the upright cross-sectional area of said shell, means for supplying liquid refrigerant into said shell whereby it may establish a level therein above said tubes, said shell providing an accumulator space above the liquid level of substantially one-quarter of the upright cross-sectional area of said shell for the separation of gaseous from liquid refrigerant, an outlet for gaseous refrigerant from said accumulator space, second impeller means for establishing a flow of a portion of said circulating heat-exchange medium through said tubes, and a by-pass for the remaining part of the circulating medium around said evaporator, whereby an energetic cooling of the portion of said medium passing through the tubes is produced and the gases of vaporization in said evaporator are permitted to separate from refrigerant liquid within said accumulator space. 135
13. In a refrigerating system comprising a brine tank, a partition in said tank to control the direction of flow therethrough and having an offset, a shell-and-tube evaporator provided with a hood member, a hood member in said partition offset, said hoods being axially aligned and spaced apart, individual impellers in said hoods, and means for driving said impellers, a cylindrical shell mounted with a horizontal axis and having heads, substantially horizontal tubes secured in said heads and located within the lower three-quarters of the upright cross-sectional area of said shell, means for supplying liquid refrigerant into said shell whereby it may establish a level therein above said tubes, said shell providing an accumulator space above the liquid level of substantially one-quarter of the upright cross-sectional area of said shell for the separation of gaseous from liquid refrigerant, an outlet for gaseous refrigerant from said accumulator space, second impeller means for establishing a flow of a portion of said circulating heat-exchange medium through said tubes, and a by-pass for the remaining part of the circulating medium around said evaporator, whereby an energetic cooling of the portion of said medium passing through the tubes is produced and the gases of vaporization in said evaporator are permitted to separate from refrigerant liquid within said accumulator space. 140

NORMAN H. GAY.
